United States Patent Office.

ANTONIO ROBIRA, OF GALVESTON, TEXAS.

Letters Patent No. 91,272, dated June 15, 1869.

IMPROVEMENT IN SYRINGE FOR DESTROYING COTTON-PLANT WORMS.

The Schedule referred to in these Letters Patent and making part of the same.

To all whom it may concern:

Be it known that I, ANTONIO ROBIRA, of Galveston, in the county of Galveston, and State of Texas, have invented a new and improved Instrument to be Used in Destroying Cotton-Worms; and I do hereby declare that the following is a full, clear, and exact description thereof, reference being had to the accompanying drawings, making part of this specification, in which—

Figure 1 is a view showing the manner of using the instrument.

Figure 2 is a diametrical section of the instrument.

Figures 3 and 4 are details of the same.

Similar letters of reference indicate corresponding parts in the several figures.

This invention relates to a new and improved instrument, which is especially adapted for use in destroying worms which infest cotton-plants.

The object is to obtain an instrument by which a fine spray, of any suitable chemical solution which will destroy the worms, can be showered upon the plants in large quantities, and which will admit of being quickly filled with the liquid, through an enlarged inlet-passage, which will close, and remain closed during the expulsion of the liquid, as will be hereinafter explained.

To enable others skilled in the art to understand my invention, I will describe its construction and operation.

In the accompanying drawings, fig. 2, I have represented, in section, the instrument in question.

It consists of a cylindrical body or barrel, D, of any suitable length and diameter to be conveniently handled.

A represents a solid piston, which is applied within the cylinder D, and suitably packed around its circumference, as shown at e, and which has connected centrally to one end a rod, a, enclosed within a hollow rod b.

These rods pass through a stuffing-box, formed on a cap, C, from which a short air-escape tube extends, for allowing the expulsion of air during the drawing back of the piston A.

Opposite the cap C, a flat-face nozzle, A', is applied to the barrel D, which is screwed in place and packed, so as not to leak around its joints, and which

is finely perforated, for causing the liquid to be expelled from the barrel in fine spray.

In the centre of this nozzle A' is an induction-tube, g, containing a valve, h, which is applied on a stem, i, and guided by a cross-bar, m, and which opens inwardly, for allowing liquid to be drawn into the barrel D, in a large stream.

It will be seen from the above description, that the instrument is provided with a nozzle, having fine discharge-passages, through which the liquid is forced slowly, in the form of spray, and that the same nozzle is provided with an inlet-tube, through which liquid can be rapidly drawn into the barrel for filling it, but which will be automatically shut at the commencement of discharging the liquid through said nozzle, and kept shut during such discharge.

This will avoid the necessity of removing the cap A' to fill the barrel with liquid, and also avoid the loss of time which would be required to draw the liquid through the fine discharge perforations.

While I prefer to adopt an instrument constructed as shown, I do not confine myself to the precise construction, as other equivalent means may be employed, which would effect the same result of discharging through fine perforations, and filling through the same nozzle containing these perforations.

With this instrument I pass between the rows of cotton, and shower over the plants a liquid containing any ingredient or ingredients which kill the worms without injuring the plants.

By having one or more persons to assist by carrying the vessels containing the liquid, ten acres or more of plants can be showered per day with a single instrument.

Having described my invention,

What I claim as new, and desire to secure by Letters Patent, is—

The instrument for destroying the cotton-worm, consisting of the cylinder D, piston A, valve h, passage g, and perforated plate A', all operating substantially as and for the purpose herein set forth.

ANTONIO ROBIRA.
